F. J. KOHLHAAS,
SHOE LACE FASTENER,
PLICATION FILED DEC. 1, 1917

1,266,823.

Patented May 21, 1918.

Inventor
Frank J. Kohlhaas
By his Attorney Philip C. Beck

UNITED STATES PATENT OFFICE.

FRANK J. KOHLHAAS, OF CALUMET, MICHIGAN.

SHOE-LACE FASTENER.

1,266,823.

Specification of Letters Patent. Patented May 21, 1918.

Application filed December 1, 1917. Serial No. 204,973.

To all whom it may concern:

Be it known that I, FRANK J. KOHLHAAS, a citizen of the United States, and a resident of the city of Calumet, in the county of 5 Houghton and State of Michigan, have invented certain new and useful Improvements in Shoe-Lace Fasteners, of which the following is a specification, reference being made to the accompanying drawing, forming a part thereof.

My invention relates to fasteners for the laces of a shoe employing strings or laces to hold the uppers snugly about the ankle, and the objects of my invention are, among other 15 things, to provide a simple and effective fastening device which is preferably attached to the center of the upper portion of the tongue of the shoe in alignment with the top eyelets or hooks of the shoe, which device 20 shall not only hold the laces in looped position as is customary when the laces are secured in a bow-knot, but also act to maintain the tongue of the shoe in its proper place between the adjacent edges of the 25 upper at all times. Furthermore my improved fastener effects a saving in the length of the shoe laces which cannot become knotted or tangled, nor are such looped laces worn or frayed when held in place by my 30 fastener which is extremely simple in construction and can be readily attached to the tongues of shoes at a slight cost.

In the accompanying drawings, Figure 1 is a face view of portions of a shoe upper 35 and tongue equipped with my improved device;

Fig. 2 is an enlarged perspective view with the clasp member raised and the looped laces in position;

Fig. 3 is a side elevation of the fastener with the clasp member lowered into lace-holding position;

Fig. 4 is a vertical sectional view taken on the line 4—4 of Fig. 3 looking in the direction of the arrow;

Fig. 5 is a top plan view of a modification of my improved fastener;

Fig. 6 is a sectional view taken on the line 6—6 of Fig. 5; and

Fig. 7 is a sectional view taken on the line 7—7 of Fig. 6 looking in the direction of the arrow.

Similar numerals refer to similar parts throughout the several figures.

Referring to Figs. 1 to 4 of the drawings, 55 8 and 9 indicate the two adjacent front por-

tions of the upper of a shoe having vertical rows of eyelets 10 and 11 respectively along their adjacent edges; 12 is the shoe tongue which is arranged between and beneath the 60

upper portions 8 and 9 and is attached to the shoe in the usual manner (not shown). 13 and 14 are the shoe laces having the looped ends 15 and 16 respectively. In the 65

upper central portion of the tongue 12 I securely affix in any suitable manner the base member 17 of my fastening device which in the present embodiment comprises the under 70

plate 18 and the top plate 19 secured to the tongue 12 arranged therebetween by rivets 75

20 as shown in Fig. 4. Projecting upwardly at right angles from the top plate 19 is the lower clasp member 21 extending in substantial parallelism with the length of the 80

shoe tongue 12 as shown in Fig. 1. The 85

clasp member 21 is preferably formed at one end, as shown in cross-section in Fig. 4, so as to provide a rounded beaded top 22; at the opposite end the hinged clip member 23, 90

preferably made of spring steel, is pivotally secured or hinged at 24 so that its outer end is vertically movable to and from the beaded top 22 as shown in Fig. 2; such outer end of the clip member 23 is formed with two dependent resilient flanges 25 and 26, each being 95

bent inwardly as shown in Figs. 2 and 4, and adapted to engage with the top 22 when in lace-holding position. The clip member 23 is raised from its locking engagement with the beaded top 22 by the projecting lug 27 100

preferably integral therewith. 28 and 29 are oppositely disposed cut out portions formed in the lower clasp member 21 and upper clip member 23 respectively, between which the looped lace ends 15 and 16 are 105

placed in bow form as shown in Figs. 1 and 2, the cut-out portions being so shaped as to make an elongated opening for the laces to pass through.

In Figs. 5, 6 and 7 I have shown a modified form of my fastener which also embodies my invention. The lower clasp member 30 is made U-shaped in cross-section as shown in Fig. 7, and may be secured to the shoe tongue 12 by rivets through holes 31 110

in the same manner as the plates 18 and 19 (Fig. 4). At one end the clasp member 30 is made with outwardly curved spring flanges 32 and 33; at the opposite end the top clip member 34, preferably made of 115

spring steel, is pivotally secured or hinged by the pin 35 so as to be vertically movable

by the projecting lug 36 integrally formed in its outer end, as shown in Figs. 6 and 7. The clip member 34 is preferably constructed with an inverted U-shape in cross-section, as shown in Fig. 7, with dependent resilient flanges 37 and 38 adapted to be engaged by, and coact with, the flanges 32 and 33 respectively in lace-holding position. 39 and 40 are oppositely-disposed cut-out 10 portions formed in the lower clasp member 30 and top clip member 34 respectively, between which the looped lace ends 15 and 16 may be placed preparatory to their being held in locking engagement by my fastener when the clip member 34 is lowered into 15 operative engagement with the clasp member 30.

The operation of my improved fastener in both its forms is substantially as follows: 20 When the shoe upper portions 8 and 9 have been drawn together over the tongue 12 by the laces 13 and 14, looped ends 15 and 16 are formed with the respective lace ends which are then laid crosswise in the cut-out 25 portion of the lower clasp members in bow-knot form as shown in Fig. 2, the upper clip member having theretofore been swung upwardly to its raised position. The clip member is then pressed downwardly into 30 substantial parallelism with the clasp member and also into locking engagement therewith, whereby the looped ends 15 and 16 are compressed and held fast without displacement in the slight opening between the 35 two cut-out portions shown in Figs. 3 and 6. When it is desired to untie the shoelaces, the clip member is swung upwardly from its locking engagement with the clasp member by the projecting lugs, and the laces' 40 ends are then released and readily removed from my fastener device. It is obvious that my fastener also prevents the shoe tongue, to which it is affixed, from slipping sideways, and getting out of its proper position 45 beneath the eyelets, and its smallness and simplicity preclude its ever becoming an inconvenience.

It will be understood that various modifications of the invention may be made in details of construction without departing from the principles disclosed in the two embodiments herein shown and described.

I claim as my invention:

1. A fastener for compressible material 55 comprising an elongated clasp member hav-

ing upwardly projecting means at one end and provided with a transverse cut-out portion in said projecting means midway in said member to form a depression, and an elongated movable clip member hinged to one end of said clasp member having a bifurcated free end provided with resilient flanges to yieldingly and frictionally engage with said upwardly projecting means on said clasp member to lock said members, 65 said flanges having transverse cut-out portions formed midway between the ends to coact with said depression to form an opening between said members whereby the compressible material is held when said members are in locking engagement. 70

2. A fastener for compressible material comprising an elongated clasp member having upwardly projecting means at one end and provided with a transverse cut-out portion in said projecting means midway in said member to form a depression, and an elongated movable clip member hinged to one end of said clasp member having a bifurcated free end provided with dependent 80 resilient flanges to yieldingly and frictionally engage with said upwardly projecting means on said clasp member to lock said members in mutual parallelism, said flanges having transverse cut-out portions formed 85 midway between the ends to coact with said depression to form an elongated opening between said members whereby the compressible material is held when said members are in locking engagement. 90

3. A shoe lace fastener comprising an elongated clasp member having upwardly projecting means affixed to one end and provided with a transverse cut-out portion to form a depression located midway between the ends of said member, and an elongated movable clip member hinged at the opposite end of said clasp member having a bifurcated free end provided with dependent resilient flanges to yieldingly and frictionally engage with said upwardly projecting means on said clasp member to lock said members when the latter are in substantial parallelism, said flanges having transverse cut-out portions formed midway between the ends to coact with said depression to form an opening therebetween, whereby the shoe laces are held compressed when said members are in locking engagement. 105

FRANK J. KOHLHAAS.
